[57] **CLAIM**

The ornamental design for a bird feeder, as shown and described.

DESCRIPTION

FIG. 1 is a perspective view of a bird feeder, showing my new design;

FIG. 2 is a rear-elevational view of the side not seen in FIG. 1, a bottle being shown in phantom lines, said phantom lines being for illustrative purposes only and not to be considered part of the design;

FIG. 3 is a side-elevational view thereof; and

FIG. 4 is a bottom-plan view thereof.

FIG. 1

FIG. 2

FIG. 3

FIG. 4
